UNITED STATES PATENT OFFICE.

MAE U. METZGER, OF MONCLOVA, OHIO.

DESIGN FOR A WOMAN'S HAT.

No. 39,793.

Specification for Design.

Patented Jan. 26, 1909.

Application filed August 28, 1908. Serial No. 450,792. Term of patent 3½ years.

To all whom it may concern:

Be it known that I, MAE U. METZGER, a citizen of the United States, residing at Monclova, in the county of Lucas and State of Ohio, have invented a new, original, and ornamental Design for a Woman's Hat, of which the following is a specification, reference being had to the accompanying drawing, forming part thereof.

The drawing is a perspective view of a woman's hat showing my new design.

I claim:

The ornamental design for a woman's hat, as shown.

MAE U. METZGER.
